FIG.4

FIG.5

FIG. 1 is a front elevational view of a clock casing showing our new design, the hands and indicia shown in broken lines being for illustrative purposes only;

FIG. 2 is a rear elevational view;

FIG. 3 is a right side elevational view;

FIG. 4 is a left side elevational view; and

FIG. 5 is a top plan view.

We claim:

The ornamental design for a clock casing, substantially as shown and described.
